UNITED STATES PATENT OFFICE.

MILTON H. SPIELMAN, OF CLEVELAND, OHIO.

DESIGN FOR A FRAME FOR A PORTABLE ELECTRIC MOTOR.

51,103.

Specification for Design.

Patented July 31, 1917.

Application filed May 13, 1916. Serial No. 97,448. Term of patent 7 years.

To all whom it may concern:

Be it known that I, MILTON H. SPIELMAN, a citizen of the United States, residing at Cleveland, in the county of Cuyahoga and State of Ohio, have invented a new, original, and ornamental Design for Frames for Portable Electric Motors, of which the following is a specification, reference being had to the accompanying drawings, forming a part thereof.

In the drawings, Figure 1 is a front elevation of my frame for portable electric motors; Fig. 2 is a side elevation of the same; and Fig. 3 is a plan.

I claim:

The ornamental design for a frame for a portable electric motor, substantially as shown in the drawings.

MILTON H. SPIELMAN.
